UNITED STATES PATENT OFFICE.

HARRISON D. KEMPTON, OF PROVIDENCE, RHODE ISLAND.

BLADE-SHARPENER.

1,332,044.

Specification of Letters Patent. Patented Feb. 24, 1920.

Application filed May 16, 1919. Serial No. 297,516.

To all whom it may concern:

Be it known that I, HARRISON D. KEMPTON, a citizen of the United States, and resident of Providence, in the county of Providence and State of Rhode Island, have invented certain new and useful Improvements 5 in Blade-Sharpener, of which the following is a specification.

This invention relates to a blade-sharpening device such as for razor blades and the like, and has for its object to provide simple, practical and inexpensive means whereby such a blade may be readily mounted in a holder above an abrading member, the 10 holder being provided with a handle by which the working pressure of the blade upon the abrading surface may be nicely controlled.

With these and other objects in view, the 20 invention consists of certain novel features of construction, as will be more fully described, and particularly pointed out in the appended claims.

In the accompanying drawings:

Figure 1— is a perspective view showing 25 my improved blade-sharpening device.

Fig. 2— is a central sectional elevation showing the blade mounted in its holder and approaching one end of its stroke.

Fig. 3— shows the blade in reversed position from that illustrated in Fig. 2.

Fig. 4— is a plan view of the blade holder.

Fig. 5— is a perspective view of a modification showing a different structure by which 35 the holder may be guided over the abrading surface.

Referring to the drawings, 10 designates the abrading member which may be a block of any suitable material provided on its 40 surface 11 with a suitable abrasive whereby the blade to be sharpened may be either honed or stropped as desired. This block is shown as being provided with longitudinally disposed grooves 12 on either edge for guiding the wheels of the holder presently described, and the ends of this block are recessed as at 13 for the purpose of assisting in reversing the blade side for side upon the reverse movements of the holder.

50 The holder itself may be constructed in any suitable way and of any suitable material but I have shown the same as provided with an axle 14 on the ends of which are mounted wheels 15 adapted to roll in the 55 grooves 12 in the abrasive block. On this axle I have mounted a yoke-shaped presser

which is preferably formed of spring wire looped about and pivotally hung upon the axle as at 16, and having a forwardly extending loop 17 and a rearwardly extending 60 loop 18 to which latter is connected the operating handle 19. Both of these loops 17 and 18 being formed of spring wire are naturally more or less yielding or resilient, whereby just the desired amount of pressure 65 may be yieldably applied to the blade in drawing the same back and forth by the handle over the abrasive surface.

In order to provide one way of releasably mounting the blade 20 on the holder I have 70 provided a pair of jaws 21 on each of which is formed a handle 22, and I have provided a spring clamp 23 which extends around the axle 14 and its edges are caused to engage the jaw plates 21 and cause them to bite and 75 grip the blade connecting it in a simple and effective way to swing about the axle of the holder, but I do not wish to be restricted to this particular means of connecting this blade to the holder, as any suitable means 80 may be employed for this purpose; neither do I wish to be restricted to the employment of wheels on the holder to run in grooves in the block, as in some cases I may form eyes 26 in the opposite ends of the axle 27, 85 to slide on longitudinally-disposed rods 28, as illustrated in Fig. 5, or any other suitable means for guiding the holder over the abrasive face of the block, may be employed.

In operating my improved blade sharpener I simply press together the two handles 90 22 and so open up the jaws to receive the blade 20. When the blade is in the position relative to the handle shown in Fig. 1, the holder is moved in the direction of the arrow 95 to draw or drag the blade so that its edge will contact with the abrading surface of the block, a pressure on the blade being yieldably exerted through the handle 19 and the yielding yoke member 17. The holder is 100 now moved to the end of the block, the blade upon reaching the recessed portion 13 naturally drops by gravity rotating on its axle 14 and hangs straight down in the recess, as illustrated by dotted lines in Fig. 2. The 105 movement of the holder is now reversed which causes the blade to contact with the edge 24 on the block thus causing the blade to be further rotated on its axle and present its opposite edge to the abrading surface 110 during the return stroke of the holder at which time a yielding pressure is exerted on

the blade by the handle through the yoke portion 18. Upon arriving at the opposite end of the block this blade-rotating operation is repeated.

5 In order to effectually prevent the edge of the blade from contacting directly with the edge of the block, which, in some instances, causes the edge of the blade to be turned or otherwise injured, I have provided a set of 10 cushioning members 25 which may be formed of strips of leather, rubber, or other suitable material which serve to raise the edge of the blade just clear of the edge of the block and so prevent direct contact one 15 with the other.

The device is extremely simple and effective in its operation and practical in its construction and by its use a blade may be quickly and accurately honed or stropped as 20 desired, one side of the block being provided with a honing surface while the opposite side is provided with a stopper surface if desired.

The foregoing description is directed 25 solely toward the construction illustrated, but I desire it to be understood that I reserve the privilege of resorting to all the mechanical changes to which the device is susceptible, the invention being defined and limited only by the terms of the appended 30 claims.

I claim:

1. A blade-sharpener comprising an abrading plate, a holder in which the blade is releasably mounted above said plate, means in 35 said plate for engaging the blade on the return stroke and causing it to turn over and present its opposite edge to said abrasive plate, a handle on said holder, and means

whereby said handle may be operated to 40 control the working pressure of the blade upon the abrading plate.

2. A blade-sharpener comprising an abrading plate, a holder in which the blade is removably mounted above said member, means 45 in the edge of said member for engaging the blade and causing it to turn over upon a reverse stroke of said holder to bring its reverse surface in operating engagement with the abrading plate, a handle on said 50 holder, and means whereby said handle may be operated to control the working pressure of the blade upon the abrading plate.

3. A blade-sharpener comprising an abrading member, a holder in which the blade is 55 releasably mounted above said member, means in said plate for engaging the blade on each return stroke causing it to turn over and present its opposite edge to the abrasive surface of said plate, a handle on said holder, 60 and flexible means between the handle and the blade whereby a yielding working pressure may be exerted upon the blade.

4. A blade sharpener comprising an abrading plate, a holder in which the blade is 65 releasably mounted above said plate, means in said plate for engaging the blade on the return stroke and causing it to turn over and present its opposite edge to said abrasive plate, a handle on said holder, means where- 70 by said handle may be caused to control the working pressure of the blade upon the abrading plate, and cushioning means on said plate for preventing injury to the blade edge when contacting therewith.

75 In testimony whereof I affix my signature.

HARRISON D. KEMPTON.
